M. H. SHOENBERG

CIGAR LIGHTER

Filed Sept. 1, 1923

INVENTOR.
Milton H. Shoenberg

Miller, Henry & Baumer
ATTORNEYS.

UNITED STATES PATENT OFFICE.

MILTON H. SHOENBERG, OF SAN FRANCISCO, CALIFORNIA.

CIGAR LIGHTER.

Application filed September 1, 1923. Serial No. 660,514.

To all whom it may concern:

Be it known that I, MILTON H. SHOENBERG, a citizen of the United States, and a resident of the city and county of San Francisco, State of California, have invented new and useful Improvements in Cigar Lighters, of which the following is a specification.

My invention has for its object a device adapted to be energized by electricity for the purpose of lighting cigars, cigarettes or the like. Other objects will appear from the drawings and specifications which follow.

These objects I attain by arranging the various elements of my lighter substantially in the shape of a watch case having a flanged opening on one side surrounding and protecting the heat element and through which the heat element is exposed, and I mount the heat element and electrical connections and switch leaf all upon a single insulating member adapted to be clamped between the front and the back of the case. Supporting posts are fixed to the insulating base and rest against insulation on the rear casing, where- by distortion is prevented when the cigar is pressed against the heating element. The heating element is mounted on the insulating base and is formed as a flat helix, thereby securing the maximum heating surface and most rigid support and is adapted to be energized by the least expenditure of current.

By referring to the accompanying specification my invention will be made clear.

Referring to the drawing:

Figure 1 represents a preferred form of my lighter in cross section on the line I—I of Figure 2.

Figure 2 shows a plan view of my lighter with the top member of the casing removed and with portions shown in cross section on the plane II—II of Figure 1.

Figure 3 shows in perspective the form of helix employed as a resistance element.

Figure 4 is a side view of my lighter.

Figure 5 is a detail of the switch leaf and its base.

Throughout the figures similar numerals refer to identical parts.

A top member of the casing is shown by the numeral 1 having a central flanged opening 2 through which the cigar or cigarette may be inserted to be ignited on the heating element 3. A circumferential wall of the casing is shown at 4 and a back plate at 5. The plates 1 and 5 and the elements between them are clamped together by a suitable plu-

rality of screws as 24, 25, 26. At 7 is shown an insulating base, preferably a mica plate, held between the flanged edge 8 of the member 4 and the top plate 1.

Adjacent of the rear plate 5 is a second insulating meinber preferably also a mica plate 9, which provides insulation and support for the other parts of the device, as more specifically pointed out below. At 10 is a stem carrying a push button 11, which latter is provided with insulating button 12, against which the spring 13 normally bears. Spring 13 is formed by a base plate 14 being preferably bent at right angles there- with and bent away from the mica base 7 to prevent heat conduction. The plate 14 ex- tends from the supporting screw 15 under the mica plate 7 and is secured in place by the aforesaid screw 15. A similar support- ing screw 16 connects to one of the terminals 17 of the energizing circuit. The opposite terminal 18 of the circuit is connected under the binding screw 19 to which also is connected the resistance wire 3, the opposite end 80 of the said resistance wire being held by the binding post 20. These posts 19 and 20 preferably bridge the space between the mica plates 7 and 9 so that the plate 7 is support- ed not only about the peripheries of the ele- 85 ments 1 and 4, but is also preferably sup- ported against distortion by the posts 19 and 20, and the screws 15 and 16, when the cigar or other pressure is applied in the di- rection of the arrow 21. The metallic piece 90 14 is on the underside of the mica plate 7 and is arched away from under the heat ele- ment, whereas the resistance 3 is on the up- per or exposed side and directly within the opening 2.

The post 20 is provided with a threaded collar 21 so that when the spring leaf 13 is pressed by the button 11 against contact 21 a current flows through the resistance coil 3, bringing the same to incandescence so 100 that a cigar, cigarette or the like inserted through the flanged opening 2 may be readily ignited. The insulating bushing 23 is provided in the member 4 for the leads 17, 18 and I prefer to provide one of the connecting screws as 24, close to this bushing, about which the terminals 17, 18 are strad- dled to lock them in place with respect to the bushing 23.

Particular attention is directed to the 110 shape of my resistance or heating element, as shown in perspective in Figure 3. This

helix is preferably of nichrome wire or other resistance wire, and is flattened or formed upon a flat mandrel, its peculiar flat shape offering a large flat incandescent surface for 5 lighting the inserted cigar and providing also a stiffer structure against pressure, and a more intense heat due to the proximity of the two flat sides of the coil. It will also be seen that all of the elements involved in the 10 electric circuit are fixed upon the single insulating plate 7, thus enabling their assembly thereon before the plate is inserted between the members 1 and 4, and greatly simplifying replacements and repairs.

15 I claim:

1. In a cigar lighter, a heating element comprising a plurality of convolutions of resistance wire formed as a flattened helix with air spaces between the respective convolutions and air spaces between the flattened portions of the helix.

2. A cigar lighter comprising a base member of insulating material, binding posts fixed thereto, a relatively flat helix with a central opening therethrough of resistance wire fixed to one binding post and switch means interposed between the other binding post and the helix.

3. A cigar lighter comprising a base member of insulating material, binding posts fixed thereto, a relatively flat helix of resistance wire fixed to one binding post and switch means interposed between the other binding post and the helix and comprising a spring leaf and attaching strip therefor, said strip centrally arched away from the base and its ends fixed thereto and on the opposite side from the helix.

4. A cigar lighter as set forth in claim 2 wherein there are attaching screws and 40 wherein the binding posts and attaching screws extend from the base and rest upon insulation independently supported and thus support the base against distortion.

5. A cigar lighter as set forth in claim 2 45 wherein there are attaching screws and wherein the binding posts and attaching screws extend from the base and rest upon insulation independently supported and thus support the base against distortion 50 and a pair of electric circuit conductors passing through a fixed bushing and straddling one of said attaching screws whereby the conductors are pinched right and left between the said last named screw and the 55 said bushing.

6. In a cigar lighter, a resistance element comprising a plurality of parallel spaced convolutions of resistance wire, said convolutions of relatively elongated form and 60 parallel with each other whereby they form a flattened helix with the flattened sides approximating each other and the heat generated on one of the sides is intensified by the heat developed in the proximate side. 65

7. In a cigar lighter, a heating element comprised of a plurality of successive convolutions of resistance wire of helical form, said convolutions flattened in two parallel planes approximating each other and an air 70 space between the planes whereby the heat generated in the convolute portions in one of the planes is intensified by the heat generated in the proximate convolute portions of the other plane.

MILTON H. SHOENBERG.
